RECESSED HOUSING FOR LANDSCAPE LIGHTING

Peter Simon, 4600 James Savage Road,
Midland, Mich. 48640

Filed May 12, 1967, Scr. No. 7,090

Term of patent 7 years

(Cl. D48—20)

Fig. 2

Fig. 1

Fig. 3

Fig. 4

FIG. 1 is a side elevational view of a recessed housing for landscape lighting embodying my new design, the bottom being broken away to indicate indeterminate length.

FIG. 2 is a plan view thereof;

FIG. 3 is a fragmentary side elevational view; and

FIG. 4 is a fragmentary side elevational view taken on line 4—4 of FIG. 2.

I claim:

The ornamental design for recessed housing for landscape lighting, substantially as shown and described.
